DESIGN FOR A BUTTON

Fred H. Fisher, Syracuse, N. Y., assignor to Morris W. Haft & Brothers, Inc., New York, N. Y., a corporation of New York

Application June 17, 1936, Serial No. 63,353

Term of patent 3½ years

To all whom it may concern:

Be it known that I, Fred H. Fisher, a citizen of the United States, residing at Syracuse, in the county of Onondaga and State of New York, and having my post-office address at 135 Sedgwick Road, Syracuse, New York, have invented a new, original, and ornamental Design for a Button, of which the following is a specification, reference being had to the accompanying drawing forming part thereof.

In the drawing:

Figure 1 is a top plan view of a button showing my new design;

Figure 2 is a side elevational view; and

Figure 3 is a sectional view taken on line 3—3 of Figure 1.

I claim:

The ornamental design for a button, substantially as shown.

FRED H. FISHER.
